Specification for Design.

Patented Jan. 24, 1922.

Application filed August 15, 1921. Serial No. 492,535. Term of patent 7 years.

To all whom it may concern:

Be it known that I, FELIX EBERHART, a citizen of the United States, residing at Newark, in the county of Essex and State of New Jersey, have invented a new, original, and ornamental Design for a Talcum-Powder Box, of which the following is a specification, reference being had to the accompanying drawing, forming a part thereof.

On the drawing:

Figure 1 is a side elevation of a talcum powder box, embodying my present invention, with the cover raised;

Fig. 2 is a side elevation of the same, with the cover in place; and

Fig. 3 is a top plan view with part of the cover torn away.

I claim:

The ornamental design for a talcum powder box, as shown.
